(57) **CLAIM**

The ornamental design for a vehicle accessory interface body, as shown and described.

DESCRIPTION

FIG. 1 is a perspective view of the vehicle accessory interface body;

FIG. 2 is a right side elevation view of the vehicle accessory interface body of FIG. 1;

FIG. 3 is a left side elevation view of the vehicle accessory interface body of FIGS. 1 and 2;

FIG. 4 is a front elevation view of the vehicle accessory interface body of FIGS. 1-3;

FIG. 5 is a rear elevation view of the vehicle accessory interface body of FIGS. 1-4;

FIG. 6 is a top plan view of the vehicle accessory interface body of FIGS. 1-5; and,

FIG. 7 is a bottom plan view of the vehicle accessory interface body of FIGS. 1-6.

The dot-dash-dot broken lines define the bounds of the claim and form no part thereof.

The broken lines in the drawings illustrate portions of the vehicle accessory interface body and form no part of the claimed design.

1 Claim, 5 Drawing Sheets
